UNITED STATES PATENT OFFICE.

JAKOB FÜRST, OF ZURICH, SWITZERLAND.

LIFT JACK.

1,420,831.

Specification of Letters Patent Patented June 27, 1922.

Application filed June 23, 1920. Serial No. 391,198.

To all whom it may concern:

Be it known that I, JAKOB FÜRST, a citizen of the Swiss Confederation, residing at Zurich, in the Swiss Confederation, have invented new and useful Improvements in Lift Jacks (for which I have filed an application in Germany, June 21, 1919, No. 44,790 x1/35), of which the following is a specification.

- 10 This invention relates to lift-jacks and its object is to provide an external plunger or lift-rod with parallelogrammic link-motion articulated to the supporting post, while the operating hand lever is pivoted on another post or otherwise movably connected with a support in such a manner as to spread the weight lifted over the two posts without complicating the operation or rendering same difficult.
- 15 20 A single hand-lever serves for lifting the weight upon the lift-rod pivoted to said lever and connected by a link to the pivot-standard or supporting post thereof, while a pivoted rest is secured to the lever so as to automatically fall into position at the lifting of said lever and to be reversed by a previously tensioned spring when the weight is to be lowered to its normal position.

I attain my object by the mechanical device shown in the accompanying drawings, in which:

Figures 1 and 2 are side elevations of the lifting-jack in two different positions; Fig. 3 is a plan of Fig. 2; Fig. 4 shows in side view separately the jack and the folded hand-lever; Figs. 5 and 6 are side elevations, showing different positions of a modified lifting-jack; Figs. 7 and 8 are side elevations of a further modified lifting-jack.

- 40 Referring first to Figs. 1 to 4, the lift-rod *a* is pivotally carried near the pivoted end of the hand-lever composed of the parts *b*, *f*, *g*, and carrying a pivoted rest *i*. The lift-rod *a* has a parallelogrammic motion with reference to the supporting post *d* by reason of the articulated parts *b* and *c* in connection with the post *d*. The hand-lever has its part *b* detachably secured by a withdrawable pin *e*, while the parts *f* and *g* of 45 the same have an articulated joint so as to render this part of the lever foldable for storing. Fig. 4 shows the lifting-jack taken to pieces ready to be placed in a tool box or the like. To the part *f* of the hand-lever

is pivoted the rest *i* which can fold alongside of said part *f* when the jack is not in use.

For a lifting operation, the parts of the jack are positioned as shown in Fig. 1, then the hand-lever is raised as shown in Fig. 2, whereby the rest *i* is permitted to fall by its own weight so as to sustain the hand-lever. Thus, the weight is jointly carried on the post *d* and the rest *i*.

To ensure the automatic folding up of the rest *i* in order to lower the weight, a spring *k* with a pull under control of an operating lever *l* is here provided; the dotted position of lever *l* in Fig. 2, clearly explains the action of the spring-pull. After the jack is placed in position and before raising the hand-lever, the spring-controlling lever *l* is turned over into position shown by full lines in Figs. 1 and 2 so as to release the pull on the rest *i* and allow the latter to drop.

To lower the weight, the lever *l* is turned as is indicated by the arrow *x* in Fig. 2 so as to tension the spring *k*, the hand-lever is then slightly raised so as to allow the spring *k* to pull back and fold the rest *i* against the hand-lever, whereafter the latter can be lowered with the weight as shown in Fig. 1.

After each lowering of the hand-lever, the small lever *l* should be turned into the position shown by full lines so that the spring *k* may not prevent the dropping of the rest *i* at a subsequent lifting operation. Naturally the lever *l* is so hinged and arranged as to securely remain in both end positions after being definitely operated.

In the modification shown in Figs. 5 and 6, the parts *a* and *d* and the lower link connecting same with the post *d*, are formed as in the previous form, while the hand-lever has its three parts foldably assembled by two articulated joints. The rest consists of a hinged toothed portion *i*¹ pivoted on the hand-lever, and of a spur *m* fast on the base plate *n* of the post *d*, the spur *m* engaging the teeth of *i*¹ for supporting the hand-lever under weight. A spring *k* can be tensioned by a lever *l* to pull *i*¹ out of engagement in order that the hand-lever may be lowered. If desired, a spring may be provided to assist in keeping the parts *i*¹ and *m* in engagement as long as is required.

In the modification shown in Figs. 7 and 8 the only difference to that shown in Figs.

5 and 6, consists in the toothed spur m^1 and the pawl i^2 for engagement with the teeth of said spur through the action of a spring o . The spring h and its tensioning lever l 5 are similar to those previously described.

The operation of the hand-lever is the same as that described with reference to the preceding figures.

I claim:

10 1. In a lifting-jack, a supporting post, a hand-lever pivoted to said post, a lifting rod pivotally carried on the hand-lever, a link pivotally connecting the lifting rod with the supporting post, a rest pivoted to

the hand-lever, and a spring and tensioning device for folding up said rest against the hand-lever.

2. In a lifting-jack, a supporting post, a foldable hand-lever pivoted to said post, a lifting rod pivotally carried on the hand-lever, a link pivotally connecting the lifting rod with the said supporting post, a rest pivoted to the hand-lever, a spur fast on the base plate of the said supporting post for engagement with said pivoted rest, and a spring and tensioning device for folding said rest against the hand-lever.

JAKOB FÜRST.
